US0D1054822S

(12) **United States Design Patent** (10) Patent No.: **US D1,054,822 S**
(45) Date of Patent: ** Dec. 24, 2024

(54) **CLAMP FOR A SHARPENING DEVICE USED
TO SHARPEN A CUTTING TOOL**

1,368,218 A 2/1921 Chenette
1,453,409 A 5/1923 Scott
1,464,442 A 8/1923 Palser
1,541,835 A 6/1925 John

(71) Applicant: **DAREX LLC**, Ashland, OR (US)

(Continued)

(72) Inventors: **Steven L. Baker**, Medford, OR (US);
Daniel T. Dovel, Shady Cove, OR (US)

FOREIGN PATENT DOCUMENTS

(73) Assignee: **Darex, LLC**, Ashland, OR (US)

AU 204125 B 2/1956
CN 216781217 U 6/2022

(**) Term: **15 Years**

(Continued)

(21) Appl. No.: **29/872,834**

(22) Filed: **Mar. 20, 2023**

Related U.S. Application Data

(63) Continuation of application No. 29/788,172, filed on Apr. 2, 2021, now Pat. No. Des. 985,350.

“User Manual for the Ermak-10 knife sharpener”; https://sharpeningtool.eu/sites/default/files/temp/instrukcia_e10_en.pdf; obtained from the Vetako website on Mar. 14, 2022; 6 pages.

1,148,303 A	7/1915	Farrar

FIG. 1 is a perspective view of the design.

FIG. 2 is a front view of the design of FIG. 1.

FIG. 3 is a rear view of the design of FIG. 1.

FIG. 4 is a top plan view of the design of FIG. 1.

FIG. 5 is a bottom plan view of the design of FIG. 1.

FIG. 6 is a right side view of the design of FIG. 1; and,
FIG. 7 is a left side view of the design of FIG. 1.

The dash-dot-dash broken lines in the drawings define boundaries of the claim and form no part thereof. The dash-dot-dash broken lines in the drawings depict portions of the clamp for a sharpening device used to sharpen a cutting tool that form no part of the claimed design.
